UNITED STATES PATENT OFFICE.

WILLIAM JOHN BURNSIDE, OF HILCOT COURT ROAD, LOWER NORWOOD,
COUNTY OF SURREY, ENGLAND.

PRINTING-TELEGRAPH.

SPECIFICATION forming part of Letters Patent No. 269,634, dated December 26, 1882.

Application filed May 31, 1882. (No model.) Patented in England April 18, 1882, No. 1,853.

To all whom it may concern:

Be it known that I, WILLIAM JOHN BURNSIDE, a subject of the Queen of Great Britain, residing at Hilcot Court Road, Lower Norwood, in the county of Surrey, England, have invented certain new and useful Improvements in Transmitting and Receiving Apparatus for Printing-Telegraphs, (for which a provisional specification has been lodged by me in Great Britain, No. 1,853, dated 18th April, 1882,) of which the following is a specification.

This invention has for its object improvements in transmitting and receiving apparatus for printing-telegraphs.

In the receiving-instruments of type-printing telegraphs I employ, as in the receiving-instruments of other printing-telegraphs, a type-wheel to which a step-by-step revolving motion is imparted, such step-by-step movements being controlled by a series of electrical pulsations, alternately of opposed polarity, which are transmitted from the sending station. The pulsations cause a rapid to-and-fro vibration between electro-magnets of an armature mounted on an axis, which also carries escapement-pallets acting with an escapement-wheel on the axis of the type-wheel. The axis of the type-wheel may either be driven by a train of clock-work or the revolving motion may be given to the escapement-wheel by the to-and-fro movement of the pallets. In the above respects the apparatus possesses no novelty. The to-and-fro oscillations of the armature are controlled by fixed stops situated on either side of a projection extending from it away from the axis. The currents are made to pass not only through the coils of the above-mentioned electro-magnets, but also through the coils of another electro-magnet employed to actuate the impression or printing lever. The weight of the lever and armature tends to cause the armature to drop away from the magnet. A spring also tends to draw away the armature, as in the receiving-instruments of other printing-telegraphs before made. So long as the alternate currents are passing through the coils of the electro-magnet the armature is not drawn up to the magnet; but so soon as the

reversals of the current cease and a current of either kind continues for a slightly longer time the armature, in connection with the printing or impression lever, is drawn to its magnet, and the pad or plateau carried by the lever strikes the paper against the type of the type-wheel, which is then opposite to it.

In order to be able to set the type-wheel to zero, the axis of the type-wheel has a radial pin standing out from it. A lever-arm is held by friction to one of the axes of the train of wheels by which the type-wheel is driven. The revolving of the axis tends to carry the lever-arm into the path of the radial pin on the axis of the type-wheel and stop the type-wheel. Each time that the impression-lever is impelled toward the type-wheel a claw upon the lever turns the arm away from the type-wheel to such a distance that the type-wheel is free to make somewhat more than one complete revolution before the detent can come into the path of the radial pin, so that the type-wheel can always be brought to zero if allowed to turn for more than, say, one complete revolution without printing.

The type-wheel I prefer to form of ebonite surrounded by a strip of soft vulcanized india-rubber, standing out from which are the several letters and characters. These are inked, as heretofore, by a small revolving cylindrical pad or roller charged with ink, which rests lightly against one point of the circumference of the type-wheel. By using one of the aniline inks the soft-rubber surface of the type-wheel can be kept charged with ink for a long time. To give the requisite forward travel to the strip of paper, the impression-lever carries a pawl to act with the teeth of a ratchet-wheel on the axis of a roughened roller, over which the strip of paper is led. As the impression-lever moves back away from the type-wheel the pawl turns the wheel one tooth, and a fixed pin then holds the pawl against the wheel and prevents the wheel overrunning. Another pawl carried by a fixed pin prevents the wheel from turning back in the reverse direction. In this way the paper is moved forward a distance after each impression.

In place of the pawl carried by a fixed pin, I sometimes fix the pawl onto the impression-lever, the impression-lever thus carrying two pawls, which act alternately into the teeth of the ratchet-wheel on the axis of a roughened roller, above mentioned. By this means I diminish the play of the lever by one-half. The paper is held down onto the above-mentioned roughened roller by another roller held down onto it by a light spring. This roller is also prevented from turning in the reverse direction by a spring catch or pawl catching into teeth formed around its circumference.

The transmitter for sending reversed currents I construct of a revolving spindle, with a radial arm standing out from it, into the path of which one or other of a number of stop-pins can be brought by the depression of a finger-key and be caused to arrest the movement of the spindle at various points of its revolution, according to the letter or sign to be printed. When a key has been depressed it remains down until another key is depressed. The depression of this second key is made to lift the first key to its previous position, so liberating the spindle and allowing it to revolve until stopped by the stop-pin of the second finger-key. Upon the spindle is a metallic wheel, against the circumference of which rests a wire brush. Strips of ivory or some other non-conducting material are let into the circumference of the metallic wheel, so that its circumference is composed of alternate strips of conducting and non-conducting material. The wheel is connected to one pole of a battery and the brush to the other. When the brush rests on any part of the metallic surface of the wheel the circuit is completed, but when it rests on the ebonite the circuit is broken. The circuit is made to pass through the coils of an electro-magnet. The armature of this magnet is alternately attracted to the magnet and drawn from it by a spring as the electric circuit is completed or broken. The armature is thus made to vibrate to and fro. The armature carries two metallic strips insulated from one another. Above and below each strip is a contact-point. The strips strike these points alternately as the armature moves to and fro, and in so doing effects reversals in another electric circuit. In this manner rapid reversals of the current in this second circuit are obtained whenever the wheel above mentioned is revolved, and whenever the wheel ceases to revolve a current of one or other kind will be passing continuously along the line. In order that the wheel may start quickly whenever its axis is liberated, the axis is coupled by a coiled spring to the shaft, which drives it. This driving-spring has therefore only to overcome the inertia of the wheel and its axis to start it into motion. In this way I insure that the first reversals of the currents in the main circuit shall be sufficiently rapid to avoid all chance of the impression-lever of the printing-instruments in the circuit being brought into action until the

revolving of the transmitter-wheel is again arrested.

On Sheets 1, 2, 3, and 4 of the drawings annexed I have shown a receiving-instrument 70 constructed as above described.

Figure 1 is a front view of the instrument; Fig. 2, a left-hand end view; and Fig. 3, a vertical section taken through the line 1 1, Fig. 2, and looking toward the right hand. Fig. 4 75 is a plan view of the instrument, and Fig. 5 shows a diagram view of the magnet-coils to show the way in which the circuit is led through them. Fig. 6 shows in plan view the parts by which the type-wheel may, whenever required, 80 be arrested at zero.

In the instrument shown the type-wheel is driven by a cord and weight; but it might be driven by a train of clock-work, as above stated.

A A are two side plates of the brass frame 85 of the instrument. At the bottom they are held at the required distance apart by bars A', and at the top by a bridge-piece, A². At the lower part of the frame is carried an axis, B, having fast upon it a ratchet-wheel, B', and 90 also a barrel, B², upon which a weighted cord can be wound, and having also loose upon it a toothed wheel, C, carrying a pawl, C', which engages with the teeth of the ratchet-wheel B', and is thereby driven in the direction shown by the 95 arrows. The toothed wheel C gears with a pinion, D', on an axis, D. A toothed wheel, D², on this axis gears with a pinion, E', on an axis, E. A toothed wheel, E², on this axis gears with a pinion, F', on an axis, F. A toothed wheel, 100 F², on this axis gears with a pinion, G', on an axis, G, by which the type-wheel H is carried, so that the type-wheel always tends to revolve in the direction shown by the arrows. On the axis G is also an escapement-wheel, G², the 105 revolution of which is controlled by the to-and-fro oscillations of the escapement-lever I', which hangs down from an axis, I. The axis has connected to it by a brass connection, I², a thin armature, I³, of sheet-iron, which can 110 vibrate to and fro between the ends of the cores of electro-magnets J J'. The oscillations of the armature are controlled by an arm, I⁴, which projects up from it, striking against stops I⁵. These stops are carried by the bridge-piece A² 115 of the frame. By placing the stops in this position the oscillation of the armature is very perfectly controlled, as it cannot be bent or deflected in either direction by the action of the magnets, and may therefore be made lighter 120 than it otherwise could be. The iron cores of the electro-magnets J are in contact with the two poles of a permanent magnet, K, and the cores of the magnets J' in contact with the poles of the permanent magnet L. The north 125 pole of one magnet is opposite to the north pole of the other magnet, and the south pole of the one opposite to the south pole of the other. The helices or coils which surround the cores J J' are so wound that when a current is passed through them it will produce an 130 opposite effect in the magnets J to that pro-

duced in the magnets J' , a positive current reinforcing or strengthening, say, the magnets J and partially or wholly neutralizing the normal magnetism of the magnets J' , while the 5 opposite effect is produced when a negative current passes. By this means when alternating currents are passed through the coils the armature will be made to vibrate to and fro between them.

10 M are the electro-magnets which are to work the impression-lever. Their cores are attached to an iron bar, M^x , which at its end is secured by screws to the two side plates, A , of the frame. The electric circuit through the helices 15 or coils which surround the cores of the magnets $J J'$ is also led through the helices or coils which surround the cores of the magnets M , as shown by the diagram, Fig. 5.

M' is the armature of the magnet M . It is 20 carried by an axis, N , which also has fixed to it the impression-lever O . The iron armature M' is fixed to an arm, M^2 , of brass, which can turn around the axis N , but which is locked by screws, as shown at Fig. 3, to an arm, M^3 , 25 which is fast upon the axis. The distance of the armature from the magnet can in this way be adjusted. The weight of the armature and the arms which carry it and the weight of the impression-lever all tend to turn the axis N in 30 a direction to withdraw the armature M' away from the electro-magnets M . A spring, U , also tends to draw the armature away from the magnet. One end of this spring is attached to the impression-lever O , the other end to a 35 cord which can be wound up more or less around a pin, U' , and in this way the force with which the spring draws the impression-lever downward can be adjusted, so that it shall have power enough to propel the paper 40 forward on its descent, and so that the armature M' shall not too readily be drawn upward by the magnet M .

The impression-lever O is best seen in Fig. 1. It carries a platen, O' , for striking upward 45 the traveling strip of paper onto the lowest letter in the type-wheel. It also carries a guard, O^2 , to hold the paper down and keep it down closely over the top of the platen. It also carries a pawl, O^3 , to engage with the teeth of a 50 ratchet-wheel, P . This ratchet-wheel has fast with it a roughened roller, P' , over which the strip of paper is led. The ratchet-wheel P and roughened roller P' turn on a pin, P^2 , which stands out from the frame of the machine. The 55 pawl O^3 is acted on by a spring, O^4 , fixed to the impression-lever. The spring turns the pawl in a direction to make it engage with the ratchet-wheel. As the impression-lever descends away from the type-wheel the pawl 60 turns the ratchet-wheel, and the back of the pawl then comes against a pin, Q , which stands out from the frame. The pawl therefore cannot get away from the ratchet-wheel and the wheel cannot turn farther than it is propelled 65 by the pawl. A pawl, R , turning upon a fixed pin, R' , prevents the ratchet-wheel turning

backward; but, as before stated, this second pawl I sometimes fix on the impression-lever, in which case a second pin, similar to Q , is fixed to the frame, and thus locks the pawl 70 when the impression-lever is held up, in a similar manner to that already described with the first-mentioned pawl. The paper is held down onto the roughened surface of the roller P' by a roller, S . This roller is carried by a forked lever-arm, S' , which turns around a fixed pin, T . The lever-arm S' has fixed to it a light spring, S^2 , which bears upon a fixed pin, S^3 , and the roller S is thereby pressed downward 80 onto the surface of the roller P' . The central portion of the roller S has fine ratchet-teeth cut across it, and a small tooth at the extremity of a light spring, S^4 , fixed to the lever-arm, engages with these teeth and prevents the roller from turning backward. This insures that the 85 paper shall not be drawn backward when the impression-lever moves upward.

V is a lever-arm on the end of the axis E . It can turn around the end of the axis, but is held by friction up to a shoulder upon it by 90 means of a spring, V' , as shown at Fig. 6. One end of the spring is fixed to the arm. The other bears against a collar carried at the end of the axis E .

G^3 is a radial pin extending from the axis 95 G . If the lever V is allowed to turn so that its bent-over end gets into the path of this radial pin, the axis G is prevented from turning. In the boss of the lever V is a notch, V^2 . Each time that the impression-lever rises 100 to a claw, O^5 , on the impression-lever O catches into this notch and turns the arm back away from the axis G , so that it will take a certain number of turns of the axis G without printing before the arm can get into the path of the 105 radial pin.

The type-wheel is made of ebonite or other equivalent hard substance, and its circumference is surrounded by a band of elastic vulcanized india-rubber, which all around its outer 110 circumference has standing out from it and formed in one piece with it the letters of the alphabet and numerals or other symbols. This elastic band is secured by cement to the circumference of the ebonite wheel. The surface 115 of the letters and numerals is kept continually charged with ink by a small roller, W , covered with absorbent material charged with one of the aniline inks, and which rests against the circumference of the wheel. It is carried 120 by a forked lever-arm, W' , which turns upon a fixed pin, W^2 . Its own weight keeps it resting against the circumference of the type-wheel, while the pressure with which it rests upon the wheel can be regulated by the counterbalance-weight W^3 .

The transmitter is shown at Figs. 8, 9, and 10. Fig. 8 shows a vertical section of the apparatus for obtaining intermittent currents; Fig. 9, a plan view of the same.

130 A A are the series of bell-crank finger-keys, ranged in a circle. Their lower ends rest against

a small endless chain, B, which rests against numerous small rollers, C, ranged in a circle. The chain is also passed around a roller, D², which, as shown, can be moved toward or away from the circle of rollers C, and the chain thereby tightened up or loosened, there being sufficient slack to allow of one finger being depressed at a time. When any one finger-key is depressed it presses against the chain and bends it inward between two of the rollers C, and when subsequently any other finger-key is depressed the finger-key first depressed will be raised by the chain to its normal position. When any one key is depressed its end comes into the path of the radial arm D', which extends outward from the axis D and obstructs the revolution of this axis. On the axis is the metallic wheel E, the circumference of which has let into it at equally-spaced intervals strips 20 of non-conducting material.

F is a wire brush bearing against the circumference of the wheel. As shown in the diagram view, Fig. 10, the axis of the wheel is connected to one pole of a battery, G. The brush is connected to the other.

So far the apparatus is the same as apparatus which has long been used; but in place of, as heretofore, driving the axis D directly by a train of gear-wheels driven by a cord and weight, I drive the axis D from the train of driving-gear through an interposed coiled spring, H, as shown at Fig. 8, in order that the axis D may rapidly be set into motion whenever it is set free to revolve.

The circuit from the battery G is, as shown in the diagram, Fig. 10, carried through the coils of an electro-magnet, I. The armature of this magnet can rock on pivots I', and is held away from the magnet by a spring, J. The armature carries two metallic strips, K L, insulated from it by interposed blocks of non-conducting material. When the armature is held away from the magnet by the spring J the ends of the strips K are drawn against conical contact-points M N, while when the armature is drawn to the magnet the strips are drawn against conical contact-points O P. Small perforations are made, as shown, in the ends of the strips for the conical contact-points to enter, as shown, to obtain good contacts. The contact-points O N are coupled to one pole of a battery and the contact-points M P to the other pole of the battery. The contact-strip K is in connection with the line, the strip L to earth. In this way rapidly-reversed currents are sent through the line-circuit whenever the wheel E of the transmitter apparatus is allowed to revolve, and whenever the wheel E stops a continuous current of one 6c or other kind passes continuously, as above explained.

I am aware that a unison-lever vibrated directly by the impression-lever, under an organization in some respects similar to that herein shown, is old, and I make no claim broadly to such subject-matter, but limit myself to the special organization shown. I am also aware that it has heretofore been proposed to make a type-wheel in a printing-telegraph entirely of rubber, and I therefore make no claim to such subject-matter.

The right to hereafter file another application upon the special type-wheel herein described, and also the right to hereafter claim in another application or applications any subject-matter herein disclosed but not specifically claimed is reserved.

Having thus described my invention, I would state that I do not claim the action of the escapement, which may be worked by any of the ordinary forms of polarized armatures; but

I claim—

1. The combination of the arm V, having the notched boss, held by friction to the axis E, the radial pin G³ on the axis of the type-wheel, and the claw O⁵ on impression-lever O, which claw enters a notch, V², in the boss of the arm V, and so operates as to move the arm V back when the impression-lever O rises, the parts all acting together, substantially as described.

2. The combination of parts for giving a forward travel to the strip of paper after each impression, consisting of impression-lever O, carrying pawl O³, pin Q for locking this pawl, the roughened roller P', the roller S and spring S² for pressing the strip of paper against the roughened roller P', and spring-pawl S⁴ for preventing roller S from turning in wrong direction, substantially as described.

3. In combination with the finger-stops A, axis D, radial arm D', contact-wheel E, coupled to one pole of a battery, and brush F, resting against the wheel and coupled to the other pole of the battery, the coiled spring H, secured at one of its ends to the axis D and at its opposite end to an axis which can be rapidly revolved by a weight or spring or otherwise, for the purpose described.

4. The combination, in a printing-telegraph, of the contact-wheel E, mechanism for imparting motion to it when it is set free to rotate, and an interposed coiled spring, one end of which is fast to the shaft of the wheel and the other to the actuating mechanism, substantially as and for the purpose set forth.

WILLIAM JOHN BURNSIDE.
